UNITED STATES PATENT OFFICE.

JOSIAH F. JOHNSON, OF SWARTHMORE, PENNSYLVANIA, ASSIGNOR TO WESTINGHOUSE ELECTRIC & MANUFACTURING COMPANY, A CORPORATION OF PENNSYLVANIA.

CYLINDER FOR TURBINE BLADES.

Application filed October 8, 1925. Serial No. 61,252.

My invention relates to elastic fluid turbines, more particularly to the blading and cylinder arrangement thereof, and has for its object the provision of apparatus of the character designated which shall afford an efficient path for the motive fluid and, at the same time, permit slight relative axial displacement between the stationary and moving parts of the turbine without undesirably affecting the operation thereof.

Apparatus embodying features of my invention is illustrated in the accompanying drawings forming a part of this specification in which:

15 Fig. 1 is a fragmentary sectional view of a double flow turbine made in accordance with my invention;

20 Figs. 2, 3 and 4 are fragmentary views of turbine blades having modified forms of a detail of my invention; and

25 Fig. 5 is a fragmentary sectional view illustrating another modification of my invention.

In the design of axial flow elastic fluid turbines it has been found that where a gradually diverging motive fluid path is formed therethrough in the shape of a continuous cored cone, the turbine has higher efficiencies than where other known forms 30 are employed because such a flow path conforms more closely than do other forms to the specific volume of the motive fluid at each point in its expansion in the turbine and its shape is such that eddies are not 35 formed in the motive fluid flow to the extent found in other designs. Disadvantages have been encountered in the manufacture of turbines designed with a motive fluid path in the form of a continuous cored cone, 40 however, due to the fact that any axial displacement of the turbine rotor and the blading or inaccuracy in length or position of blades, affects the radial clearances of the blades. This disadvantage is present, especially 45 in turbines of the double flow type, embodying two cored conically shaped motive fluid paths with opposed ends. With such apparatus, axial displacement of the rotor increases the radial clearances of the 50 moving blades at one end of the turbine and decreases them at the other end. Decreasing the radial clearances of the blades entails danger of rubbing between the stationary and moving parts, while increasing the ra-

dial clearances with unshrouded blades increases the losses due to leakage over the ends of the blades.

55 My invention is therefore particularly applicable to turbines of the double flow type and has for its particular object to provide 60 a turbine of the character designated in which a slight axial displacement of the turbine rotor or inaccuracy in length or lateral position of blades does not adversely affect the operation of the turbine. In accordance 65 with my invention, I provide a gradually diverging motive fluid path in the shape of a cored conical passage and provide, opposite the ends of the blade rows, a series of 70 offset axially extending steps. The roots of the blades or spacing pieces therebetween, adjacent an inclined surface, are formed to conform with said surface as shown and described in the application of Francis Hodgkinson, Serial No. 688,296, filed January 75 24, 1924, and assigned to the Westinghouse Elec. & Manufacturing Company. With a cylinder and blade arrangement formed in this manner, the motive fluid is free to flow 80 undisturbed in a gradually diverging path through the turbine and thus permit the turbine to be operated at the highest possible efficiency.

85 Referring now to the drawings for a better understanding of my invention I show 90 in Fig. 1 at 10 a fragment of a turbine casing enclosing a rotor 11. As shown, the turbine is of the double flow type having a motive fluid inlet at 12 from which the motive 95 fluid flows in opposite directions to the exhaust as indicated at 13. The casing 10 is so formed that the path of the motive fluid passing therethrough forms two cored cones with opposed ends as shown. Carried by the casing 10 are a plurality of rows of stationary blades 16-16 which interleave and cooperate with like rows of moving blades 17-17 carried by the rotor 11. The blade roots, or spacing pieces between the blades 16-16 are formed with inclined end surfaces as shown at 18-18, adjacent the surface of the cylinder 10, in order to conform to the conical path of the motive fluid. The moving blades 17-17 are arranged so that their ends extend beyond the inclined surface of the blade roots or spacing pieces between the stationary blades 16-16. Opposite 100 the ends of the moving blades 17-17

the cylinder 10 is bored so as to present a series of offset, axially extending steps 19-19. With this arrangement it will be apparent that axial displacement of the rotor 11 within the limits of axial clearances does not affect the radial clearances of the moving blades 17-17. The rotor 11 is shown, for the purpose of illustration, as having, for a part way, an approximately 10 conical surface with axially extending steps 21-21 formed thereon opposite the ends of the associated stationary blades 16-16.

Referring to Figs. 2, 3 and 4, I show shrouding means for blades which may be 15 employed to better provide a continuous conical path for the motive fluid and which are adapted to minimize motive fluid leakage over the tops of the blades. In Fig. 2 a blade 31 having its tip so shaped as to aid in forming a conical path for the motive fluid is arranged to rotate opposite an axially extending surface 32. Provided on the blade 31 is a shroud 33 having upstanding sides forming packing members 34 and 20 36 with close radial clearance with respect to the surface 32. In Fig. 3 the shroud 33 has one upstanding edge 37 at one side of the blade and having close radial clearance with respect to the surface 32. Fig. 4 is 25 similar to Fig. 3 except that a packing member 38 is formed midway of the shroud 33 which prevents eccentric loading of the shroud when applied to moving blades. With either form of shrouding shown, the 30 motive fluid is confined to its cored conical path in the turbine and motive fluid leakage over the blades is reduced to a minimum.

In Fig. 5, I show a blading having a well-known form of shrouding at 26-26 designed to permit greater radial clearances of the blades and extending axially of the blades, as at 27-27, in order to minimize leakage of the motive fluid over the ends of the blades. With this form of blading the 40 tips of the blades, either moving or stationary, or both, may be inclined and the shrouding forms therewith a conical path for the motive fluid. With this form, of course, the roots of the blades or spacing pieces between the blades are made with inclined surfaces 45 18 adjacent the blade carrying elements so as to cooperate in forming the conical motive fluid path. With this modification the axially extending surfaces opposite the tips of the blades are formed in the same manner 50 as shown in Fig. 1.

From the foregoing it will be apparent that I have devised a turbine having a cored 60 conical path for the motive fluid flowing therethrough and in which the adverse effects on operation caused by a slight axial displacement of the rotor are minimized.

While I have shown my invention in several forms, it will be obvious to those skilled 65 in the art that it is not so limited, but is

susceptible of various other changes and modifications, without departing from the spirit thereof, and I desire, therefore, that only such limitations shall be placed thereupon as are imposed by the prior art or as are specifically set forth in the appended claims.

What I claim is:

1. In a turbine, means providing in part a gradually diverging motive fluid flow 75 passage, a blade having its longitudinal axis normal to the longitudinal axis of the turbine and having close radial clearance with respect to the opposed surface of the turbine, an offset portion extending parallel to the longitudinal axis of the turbine provided on the surface opposed to the blade, and means carried by said blade and cooperating with the first-mentioned means to define said diverging passage.

2. In a reaction turbine, the combination of relatively rotatable elements defining in part a gradually diverging motive fluid passage, interleaving rows of blades carried by the elements, longitudinally extending surfaces provided in the element describing the gradually diverging passage opposite each of the rows of blades carried by the other element, and means provided on the blades for minimizing leakage over the tips thereof, said means cooperating with the relatively rotatable elements to define a diverging passage.

3. In a double flow reaction turbine, the combination of a rotor and a stationary blade carrying element defining in part two cored frustro-conically shaped motive fluid passages with opposed ends, a plurality of rows of moving blades carried by the rotor and having close radial clearance with respect to the stationary blade carrying element, a plurality of rows of stationary blades mounted in the stationary blade carrying element and interleaving with the moving blades, offset portions provided in the frustro-conical surfaces to provide uniform radial clearances for the opposed blading, and shrouding on the blades opposite the frustro-conical surfaces forming continuations of said surfaces at the offset portions.

4. In a turbine, the combination of a plurality of rows of interleaving stationary and moving blades, a stationary blade carrying element having an interior contour forming in part the frustum of a cone from which the blades protrude, a rotor carrying the moving blades and defining with the stationary blade carrying element a cored frustro-conically shaped passage for the motive fluid, surfaces extending in an axial direction provided in the stationary blade carrying element adjacent the tips of the moving blades, and shrouding on the moving blades cooperating with said stationary blade carrying element to form the frustum of a cone.

5. In a turbine, the combination of a stationary blade carrying element having its blade holding surface inclined to the longitudinal axis of the turbine, a rotor carrying a plurality of rows of moving blades and defining with the stationary blade carrying element a motive fluid passage inclined to the longitudinal axis of the turbine, said stationary blade carrying element being machined in steps extending in a longitudinal direction opposite the tips of each of the rows of moving blades, and means provided on the blades for minimizing leakage over the tips thereof, said means conforming to the contour of said inclined surface. 15
